Inventor:
Gustavus Arnd

United States Patent Office.

GUSTAVUS ARND, OF NEW YORK, N. Y.

Design No. 3,009, dated May 5, 1868.

DESIGN FOR A STAKE TO MARK GRAVES.

The Schedule referred to in these Letters Patent and making part of the same.

TO ALL WHOM IT MAY CONCERN:

Be it known that I, GUSTAVUS ARND, of the city, county, and State of New York have invented a new and ornamental Design of Stake for Enclosing Graves; and I do hereby declare the following to be a full, clear, and exact description thereof, which will enable those skilled in the art to make and use the same, reference being had to the accompanying drawing, forming part of this specification, in which drawing—

Figure 1 represents a front view of my stake.

Figure 2 is a side elevation thereof.

Similar letters indicate corresponding parts.

This invention relates to a design for a stake for enclosing graves, the principal feature of which is a shoulder, which indicates the division between the shank and the head of my stake, and which imparts to my stake a peculiar appearance, distinct from ordinary stakes generally used for the same purpose.

A represents my stake, which is composed of two distinct parts, viz, the head, *a*, and the shank, *b*. At the point where the two parts join, a shoulder, *c*, is formed, which imparts to my stake a distinct appearance.

Having thus described my invention, what I claim as new, and desire to secure by Letters Patent, is—
The design of a stake for enclosing graves, as shown and described.

GUSTAVUS ARND.
